UNITED STATES PATENT OFFICE.

JAMES E. WRIGHT, OF BAY CITY, MICHIGAN.

NON-GLARING HEADLIGHT.

1,138,712.

Specification of Letters Patent. Patented May 11, 1915.

Application filed August 7, 1914. Serial No. 855,628.

To all whom it may concern:

Be it known that I, JAMES E. WRIGHT, a citizen of the United States, residing at Bay City, in the county of Bay and State of Michigan, have invented certain new and useful Improvements in Non-Glaring Headlights; and I do hereby declare the following to be a full, clear, and exact description of the invention, such as will enable others skilled in the art to which it appertains to make and use the same.

This invention relates to headlights and pertains more particularly to headlights such as are used on automobiles, interurban cars and other vehicles.

The purpose of the invention is to produce a headlight of simple construction that will throw a beam of light sufficiently far ahead, but that will prevent the glare produced by headlights of ordinary construction, from which the light is usually thrown upwardly as well as laterally and downwardly. Such lights throw glaring rays into the eyes of pedestrians and travelers in passing vehicles, and it is to provide a headlight from which this source of difficulty has been eliminated that my present headlight has been devised.

In the drawings, Figure 1 is a vertical longitudinal section of a headlight embodying my improvement. Fig. 2 is a horizontal section on the line 2—2 of Fig. 1. Fig. 3 is a front view.

As is clearly shown in the drawings, the device consists of a lamp 1, which may be either a gas lamp, an incandescent lamp, or an arc lamp.

The lamp is mounted at the small or rear end of a metal hood 2. This hood is preferably circular, or nearly so, in cross section, but its top 3 is preferably arranged with its axis horizontal, while its bottom 4 is inclined downwardly. The rear end 5 of the hood is so shaped as to form a cavity in which the lamp 1 is received, the lamp being so located with reference to the top and bottom of the hood that its rays will not be projected upwardly.

It will be seen that the rays of the lamp will flare out in three directions, downward, to the right and to the left.

The flaring bottom 4 is made non-reflecting, as by covering with lamp black, or any other suitable means, thereby preventing the rays from the lamp being reflected upwardly from the inclined bottom 4.

Back of the lamp is a curved reflector 6 so shaped that the rays reflected by it will not be projected upwardly and out of the hood, but will only be projected against the reflecting top 3, from which they are deflected downwardly, or else will be thrown straight ahead.

By the means above described, I have produced a headlight that will throw a sufficiently bright beam straight ahead and will sufficiently diffuse to the right and left and will also diffuse downwardly, but no strong rays of light can be projected upward above the level of the top 3, thereby reducing the liability of throwing a glaring light into the eyes of persons ahead.

Having thus described my invention, what I claim and desire to secure by Letters Patent is:

1. In a headlight, the combination with a source of light and a suitable reflector back of said light, of a curved hood, the upper part of which is disposed with its axis substantially horizontal, the upper part of said hood lying in approximately the horizontal plane of the source of light, said hood formed with a laterally flaring reflecting surface and a downwardly flaring non-reflecting surface.

2. In a headlight, the combination of a reflecting hood, the upper part of which is disposed with its axis substantially horizontal, said hood formed with outwardly flaring side surfaces and downwardly flaring bottom surfaces, a source of light located at the small end of said hood substantially in the plane of said top surface, the bottom surface of said hood being non-reflecting, for the purposes set forth.

3. In a headlight, the combination of a

reflecting hood, the upper part of which is disposed with its axis substantially horizontal, said hood being formed with flaring side and bottom surfaces, a source of light located at the small end of said hood, the lower surface of the hood being non-reflecting for the purposes set forth.

In testimony whereof, I affix my signature in presence of two witnesses.

JAMES E. WRIGHT.
